CLOTHES WRINGER

Anthony P. Barcus, Dayton, Ohio, assignor to
General Motors Corporation, Dayton, Ohio, a
corporation of Delaware

Application October 31, 1942, Serial No. 464,047

6 Claims. (Cl. 68—255)

1

This invention relates to power driven clothes wringers.

It is common for the wringers of washing machines to be provided with an index release which will allow the wringer to be positioned at selective angles around a vertical axis in alignment with the vertical drive shaft of the wringer. It has been necessary to instruct the operator of the wringer to shift the driving control to the neutral position to disconnect the power from the wringer mechanism before indexing. If the driving control is not shifted to the neutral position, there is a great danger that during indexing the power driven wringer will rotate with its drive shaft and spin around the vertical axis and injure the operator.

It is an object of my invention to provide a power driven wringer with a simple practical index release mechanism which will simultaneously shift the driving control to the neutral position when the index latch is released.

In order to provide added safety protection for power driven clothes wringers, the instinctive type of wringer has been developed in which a tug on the clothes will move the body of the wringer to release the pressure on the rolls.

It is another object of my invention to provide a simple means which will discontinue the power drive for the wringer rolls when there is a tug on the clothes and/or movement of the body of the wringer and which presents no resetting difficulty.

These objects are attained by providing a power driven clothes wringer which is adjustable about the axis of its drive shaft when the index latch is released. The index latch operates a vertical sliding member to move the normal control of the drive mechanism to the neutral or de-clutched position. The body of the wringer is made movable with respect to its support. The normal control mechanism is provided with cam surfaces which are moved into engagement with a projection extending from this wringer support to move the normal control to its neutral position in which the drive mechanism is disconnected from the power source.

Further objects and advantages of the present invention will be apparent from the following description, reference being had to the accompanying drawings, wherein a preferred form of the present invention is clearly shown.

In the drawings:

Fig. 1 is a vertical sectional view through one end of a wringer embodying my invention;

2

Fig. 2 is a sectional view taken along the lines 2—2 of Fig. 1;

Fig. 3 is a sectional view taken along the lines 3—3 of Fig. 1;

Fig. 4 is a sectional view taken along the lines 4—4 of Fig. 1.

Fig. 5 is a fragmentary view of the helical surface provided on the bevel pinions; and

Fig. 6 is a vertical sectional view through the bearing post 333.

Referring now more particularly to Figs. 1 to 5, there is shown a simplified form of the invention. In this form, the usual supporting post 301 contains a drive shaft 303 connected to the upper shaft 305 by a fork socket and pin connection. The shaft 305 is connected by a pin 307 to a double ended sleeve 309 which contains at its upper and lower ends the blunt ended wound springs 311 and 313. Rotatably mounted on the shaft 305 are the upper and lower bevel drive gears 315 and 317 which mesh with the crown gear 319. The crown gear 319 connects through a coupling 321 with the roll shaft 323 of the lower wringer roll 324. The lower roll 324 is supported in bearings 322 supported in the side stiles 320. The upper roll 424 is frictionally driven by the lower roll 324 and is similarly supported. The beveled gears 315 and 317 are provided with long bearing sleeves to provide an adequate bearing surface upon the shaft 305. The long bearing sleeves are preferably rigidly connected to the gears 315 and 317. However, the arrangement is operative if the sleeves are either loose or rigidly connected to either the gears or the shaft.

The beveled gears 315 and 317 are each provided with a helical face adjacent the wound spring. This helical face is provided with a shoulder as is better shown in Fig. 5. Surrounding the sleeve 309 is a shifting collar 325 provided with an annular groove 327 receiving the eccentrically located pin 329 extending from the shaft member 331 which is rotatably mounted in the bearing post 333 provided upon one side of the gear case 335. The shaft member 331 is provided with a

shaft 337 of reduced proportions for carrying the control handle 338. The shaft member 331 is drilled transversely to receive the spring pressed pin 332 for engaging notches in the interior of the bearing posts 333 as shown in Fig. 6. By this arrangement, the shaft 337 and the control handle 338 are resiliently held in either the forward, neutral, or reverse positions. Of course, this spring latching arrangement can be overcome by operating the handle 338 or any of the declutching release mechanisms.

50

When the shaft 337 is moved in one direction of rotation, the pin 329 will lift the shifting collar 325 which carries a sliding key 339 upwardly into the path of the adjacent blunt end of the wound spring clutch 311. This causes one blunt end of the wound spring to engage the shoulder provided by reason of the helical surface on the face of the gear 315 while the other blunt end engages the key 339. This key rides in a slot provided for it in the sleeve 309 to provide a driving connection between the shaft 305 and the bevel gear 315 which drives the crown gear 319 of the roll shaft 323. The wound spring 311 in this case expands against the inner wall of the sleeve 309. The sleeve 309 is provided with apertures 341 to permit the escape of lubricant from the portion of the sleeve occupied by the wound springs so that a satisfactory grip will be provided between the wound spring and the sleeve 309. The key 339 is moved downwardly when the shaft 337 is moved in the opposite direction to engage the end of the wound spring to cause driving engagement between the shaft 305 and the gear 317 in a manner similar to that described for the wound spring 311.

I provide rotation between the wringer and its support. This is done by providing a downward extension 345 of the gear case 335. This downward extension is in the form of a cylinder having its center line exactly in alignment with the centers of the line of contact between the beveled gears 315 and 317 on the one hand and the crown gear 319 on the other hand. This cylindrical extension 345 is rotatably mounted within the wringer support 347 which in turn is rotatably mounted upon the upper end of the supporting post 301 upon the axis of the drive shaft 303. The movement of the wringer with respect to the wringer support is limited by the screw 349 which extends through a rubber bushing within the wall of the wringer support 347 and is locked in the cylindrical extension 345. This allows a limited amount of movement of the wringer with respect to the wringer support 347 opposed by the elastic force of the rubber which will tend to keep the wringer in a normal position with respect to its support 347. Inasmuch as the center of the cylindrical extension 345 is in exact alignment with the centers of the line of contact between the gears above there will be no rotating reaction due to the transmission of the force by the gears because of this relationship.

To make it possible for the wringer drive to be stopped and particularly to throw the drive mechanism and the shifting collar 325 to the neutral position in an emergency, I have provided an extension 355 of the wringer support 347 to which is bolted a vertical plate 357 which in turn is provided with an aperture. The portion of the vertical member 357 surrounding this aperture is provided with an upper set of humps 359 and a lower set of humps 361. The shaft member 331 is provided with an upper projection 363 and a lower projection 365. When the shaft 337 is moved by its operating knob or lever 338, a distance of about 30° to place the driving mechanism into engagement with the shaft 305 to drive the wringer rolls in either direction, the projections 363 and 365 will be just out of contact with the humps 359 and 361 as shown by the dot and dash line in Fig. 3. Any movement of the right end of the wringer such as would be caused by tugging upon the clothes being fed into the rolls or by pushing upon any portion of the wringer will cause one of the humps to en-

gage either of the projections 363 or 365 to move the shaft 331 and the collar 325 to the neutral position which will stop the driving of the wringer rolls.

An index mechanism with an interlock is also provided. For this purpose, the supporting post is provided with a flange 371 containing apertures. These apertures are of suitable size to receive the index latching pin 373. This latching pin is slidably mounted in the wringer support and pressed downwardly by the compression spring 375. An index release lever 377 is provided for raising the index latching pin 373. The outer end of this index release lever 377 is provided with a knob 379 and also extends through an aperture in the lower end of a vertical sliding member 381 having slots 383 and 385 which allows the member 381 to move vertically. The upper end of the member 381 is bent 180° and provided with a pair of humps 387.

The shaft 331 is provided with a set of horizontal projections 389, one of which will be moved just out of contact with one of the humps 387 when the handle shaft 337 is moved 30° in either direction from the neutral position to cause operation of the wringer. The movement of the projection 389 in one direction 30° is illustrated by the dot and dash lines in Fig. 11. When the index release knob 379 is pushed downwardly, the vertical sliding member 381 will be lowered, causing the engagement of one of the humps 387 with the nearest projection 389 to move the shaft 331 and the shifting collar 325 to the neutral position to declutch the driving mechanism from the shaft 305. At the same time the index release lever 377 will raise the index latching pin 373 to allow the wringer to be turned upon the supporting post 301.

Thus, in this instinctive type of wringer, I have provided a simple control which will declutch the drive mechanism upon any indexing or whenever the wringer is moved by a tug on the clothes passing through the rolls or by pushing or pulling upon the wringer.

While the form of embodiment of the invention as herein disclosed, constitutes a preferred form, it is to be understood that other forms might be adopted, all coming within the scope of the claims which follow.

What is claimed is as follows:

1. A wringer including a frame, rolls mounted in the frame, a bevel gear driving mechanism for the rolls having an operative position for operating the rolls and an inoperative position for rendering the rolls inoperative, said drive mechanism including a substantially vertical drive shaft, a pivotal support for said frame including a pivotal connection providing a substantially vertical pivot eccentric to said drive shaft having its axis located substantially in alignment with a point of contact of the bevel gears of the driving mechanism for pivotally mounting the entire frame and the driving mechanism, and means responsive to the pivoting of said frame and driving mechanism upon said eccentric vertical pivot for moving the driving mechanism from operative to inoperative position.

2. A wringer including a frame, rolls mounted in the frame, a driving mechanism for the rolls having an operative position for operating the rolls and an inoperative position for rendering the rolls inoperative, said drive mechanism including a substantially vertical drive shaft, a pivotal support for said frame including a pivotal connection providing a substantially vertical

pivot eccentric to said drive shaft for pivotally mounting the entire frame and the driving mechanism, and means located on the opposite side of said vertical shaft from said vertical pivot and responsive to the bodily movement of the driving mechanism with respect to said support for moving the driving mechanism from the operative to the inoperative position.

3. A wringer including a frame, rolls mounted in the frame, driving mechanism for the rolls including a gear case fixed to said frame, said gear case being provided with reversing gearing having forward, reverse and neutral non-driving inoperative positions, a control device carried by the gear case for moving said reversing gearing selectively into said positions, a support beneath said frame and gear case, said gear case being mounted for movement relative to said support, said support being provided with a fixed projection extending upwardly into the path of movement of said control device, said control device being provided with means cooperating with said fixed projection effective upon a predetermined movement of the case and frame with respect to said support for moving the device from one of the operating positions to the inoperative position.

4. A wringer including a frame, rolls mounted in the frame, driving mechanism for the rolls including a gear case fixed to said frame, said gear case being provided with reversing gearing having forward, reverse and neutral non-driving inoperative positions, a control device carried by the gear case for moving said reversing gearing selectively into said positions, a support beneath said frame and gear case, said gear case being mounted for movement relative to said support, said control device including an operating shaft protruding from said gear case and having operating means thereon, said support being provided with a fixed projection extending into the path of movement taken by said operating means when

said gear case is moved relative to its support for moving the operating means and shaft and said control device from one of its operating positions to its neutral inoperative position.

5. A wringer including a frame, rolls mounted in the frame, driving mechanism for the rolls including a gear case fixed to said frame, said gear case being provided with reversing gearing having forward, reverse and neutral non-driving inoperative positions, a control device carried by the gear case for moving said reversing gearing selectively into said positions, a support beneath said frame and gear case, said gear case being mounted for movement relative to said support, said control device including an operating shaft protruding from said gear case and having an operating handle thereon for moving the control device into any of its positions, said control device having an operating means thereon, said support being provided with a fixed projection extending into the path of movement taken by the operating means when said gear case is moved relative to the support for engaging and moving the operating means and the control device from one of its operating positions to its neutral inoperative position.

6. A swinging wringer having a frame, rolls mounted in the frame, a gear case connected to the frame containing reversing gearing for driving the rolls, a control device including a rotatable operating shaft parallel to the axes of the rolls protruding from the side of said gear case, a swing lock including a swing lock releasing member, a handle on said shaft for normally operating said control device, to forward, reverse and neutral positions, and means located at the side of said gear case operatively connecting said releasing member and said protruding portion of said shaft for rotating said shaft to the neutral position upon operation of the releasing member.

ANTHONY P. BARCUS.
